His Attorney.

UNITED STATES PATENT OFFICE.

PAUL SCHADE, OF HERMSDORF, NEAR BERLIN, GERMANY, ASSIGNOR TO GENERAL ELECTRIC COMPANY, A CORPORATION OF NEW YORK.

ARRANGEMENT FOR LOCALIZING DISTURBED AREAS IN ELECTRIC MAINS.

Application filed May 3, 1922. Serial No. 558,224.

To all whom it may concern:

Be it known that I, PAUL SCHADE, a citizen of the German Republic, residing at 14 Kneippstr., Hermsdorf, near Berlin, Germany, have invented certain new and useful Improvements in Arrangements for Localizing Disturbed Areas in Electric Mains, of which the following is a specification.

This invention relates to an arrangement 10 for localizing disturbed areas in electric mains.

It has already been proposed to localize disturbed areas in electric mains, the sections of which consist of several parallel branches, 15 by utilizing the voltage drop between corresponding points of the different branches. For this purpose each of the branches with the exception of the two outer ones is connected with two other branches across voltage coils and the voltage coils placed in the 20 connecting leads co-operate with current coils in the parallel conductors of the system. The branch of the mains in which the voltage drop differs from that in the other 25 branches is then automatically cut out of circuit.

Cases may, however, occur in which this arrangement will no longer work with certainty. In particular failure may arise if 30 the system is mainly loaded inductively. In order to effect also the cutting out of the disturbed section with certainty, the improved arrangement according to this invention, is such, that the connecting leads 35 are united to form a completely closed connecting circuit. The possibility is then given to effect the interruption of the current by means of relays, in which merely the voltage coils placed in the connecting 40 leads co-operate, while the current coils placed in the parallel branches in the known arrangement are eliminated.

In the connection of the branches of the mains by a closed connecting circuit a 45 difficulty arises, however, in the case of an even number of parallel branches. If, for instance, there exist, as shown in the drawing, four parallel branches 1—2—3—4 and a fault occurs in branch 1, a balancing current 50 flows to this branch across the connecting leads in one path from the branches 3—2—1 and in another path from the branches 3—4—1. In the connecting leads which belong to the branches 2, 4 there flows a current directed towards the branch and a 55 current directed away from the branch, so that the relays belonging to this branch do not come into action. In the branch 3 on the other hand the direction of the current in the connecting leads belonging to it is 60 the same, that means either towards the branch or away from it, exactly as in the disturbed branch. Consequently the relays for these two branches 1, 3 respond simultaneously. Besides the faulty branch 1 thus 65 the sound branch 3 is also cut out.

This undesired cutting out of a sound branch from several parallel branches may be avoided by providing between the branches not one only, but at least two connecting circuits. Care must, however, be taken that the succession of the branches with relation to the connecting circuits of the parallel branches is a different one and two branches which in relation to the connecting circuit are situated at 180° opposite 70 each other must not have this situation in relation to the other connecting circuit. The relays of the various connecting circuits belonging to a certain branch are then brought 75 into co-operation in any suitable manner and operate for instance series contacts of an auxiliary circuit, so that the cutting out of the faulty branch only takes place, since in each of the connecting circuits the connecting leads belonging to the branch in question 80 show the same directions of the currents.

In the drawing the improved arrangement is shown in a case in which the section of the mains consists of four parallel branches 90 and always two complete connecting circuits co-operate. The parallel branches are indicated by the letters of reference a_1 , a_2 , a_3 and a_4 . They are, at the sub-stations, directly connected in the customary way by 95 bus bars b and b' . Of the two connecting circuits serving for the guarding and automatic cutting out, the one contains the voltage coils c_1 , c_1' , c_2 , c_2' , c_3 , c_3' , c_4 , c_4' and the other the voltage coils d_1 , d_1' , d_2 , d_2' , d_3 , d_3' , d_4 , d_4' . In the former the succession of the sep- 100

arate parallel branches is such, that the connecting circuit starting from a_1 passes across a_2 , a_3 , a_4 and hence back to a_1 , while the second connecting circuit starts from a_1 and passes across a_3 , a_2 , a_4 back to a_1 . Between the points of the mains connected by the bus bar b and the points connected by the balancing circuit, choking coils e are placed in the parallel branches for the purpose of artificially increasing the voltage drop. In each of the parallel branches a_1 , a_2 , a_3 , a_4 there is also placed a switch f . Arranged to be operated by the coils c and d are the relays g provided for the purpose of closing the circuits by which the various operating coils h of the switches f are connected to a suitable source of current. A catch i biased to a position in which it engages a projection on the operating rod of the switch may be utilized for the purpose of locking the switch in open position. Any other suitable means may be used for the purpose of opening one of the switches f in response to the condition produced in the coils c and d by a fault on one of the branches of the main.

If a fault occurs in the branch a_3 balancing currents will appear in the connecting circuit. At a certain moment the direction of the flux produced by the various coils c and d is as indicated in the drawing by arrows. For the first connecting circuit the arrows start at both sides from the branch a_1 and meet at the branch a_3 . In the other connecting circuit on the other hand the arrows start from the branch a_4 and meet at the branch a_3 , owing to the altered succession of the parallel branches.

The relay affected by the coils c_3 and c_3' on the one hand and the relay affected by the coils d_3 and d_3' on the other hand then both operate to cut out the branch a_3 by opening the switch f placed in this branch. All the other branches remain in circuit as in them, not more than the relay in one of the connecting circuits is operated to cut out the branch.

It will be understood that the arrangement may be varied in details without departing from the spirit of the invention.

What I claim as my invention and desire to secure by Letters Patent is:

1. A system of the class described comprising a bus bar, a plurality of conductors arranged to be interconnected with said bus bar, a plurality of switches each arranged to connect one of said conductors to said bus bar, and means comprising a plurality of closed circuits each arranged to interconnect all of said conductors in different succession for selectively operating said switches to disconnect any conductor in which a fault occurs.

2. A system of the class described comprising a bus bar, a plurality of conductors

arranged to be interconnected with said bus bar, a plurality of switches each arranged to connect one of said conductors to said bus bar, and a plurality of relays each arranged to control the operation of one of said switches in response to a fault in the corresponding conductors, the operating coils of said relays being connected in a closed circuit arranged conductively to interconnect corresponding points of said conductors.

3. A system of the class described comprising a bus bar, a plurality of conductors arranged to be interconnected with said bus bar, a plurality of switches each arranged to connect one of said conductors to said bus bar, a relay adapted to control the operation of each switch and provided with operating coils connected in a closed circuit arranged to interconnect said conductors in one succession, a second relay adapted to control the operation of each switch and provided with operating coils connected in a second closed circuit arranged to interconnect said conductors in a different succession, and an operating coil for each switch which is arranged to be energized only when the corresponding relay in each closed circuit is energized.

4. A system of the class described comprising a bus bar, a plurality of conductors arranged to be interconnected with said bus bar, a plurality of switches each arranged to connect one of said conductors to said bus bar, a relay adapted to control the operation of each switch and provided with operating coils connected in a closed circuit arranged to interconnect said conductors in one succession, a second relay adapted to control the operation of each switch and provided with operating coils connected in a second closed circuit arranged to interconnect said conductors in a different succession, an operating coil for each switch which is arranged to be energized only when the corresponding relay in each closed circuit is energized, and a plurality of choke coils each arranged to be connected in series with one of said conductors.

5. A system of the class described comprising a bus bar, a plurality of conductors arranged to be interconnected with said bus bar, a plurality of switches each arranged to connect one of said conductors to said bus bar, a plurality of relays adapted to control the operation of each switch, the operating coils of each relay being connected in a different closed circuit, and all of said closed circuits being arranged to connect said conductors in different successions, and an operating coil for each switch arranged to be energized only when the corresponding relay in each closed circuit is energized.

6. A system of the class described comprising a bus bar, a plurality of conductors

arranged to be interconnected with said bus bar, a plurality of switches each arranged to connect one of said conductors to said bus bar, a plurality of groups of relays each connected in a different closed circuit and all of said closed circuits being arranged to connect said conductors in different succession. **10**

5 group being adapted to control the operation of one of said switches, the operating coils of each relay in a group being con-

In testimony whereof I affix my signature.

PAUL SCHADE.
